UNITED STATES PATENT OFFICE.

OTIS A. MYGATT, OF NEW YORK, N. Y.

DESIGN FOR A REFLECTOR FOR ARTIFICIAL LIGHTS.

SPECIFICATION forming part of Design No. 35,757, dated February 18, 1902:

Application filed June 10, 1901. Serial No. 64,055. Term of patent 7 years.

To all whom it may concern:

Be it known that I, OTIS A. MYGATT, residing at New York, in the county of New York and State of New York, have invented and produced a certain new and useful Design for a Reflector for Artificial Lights, of which the following is a specification, reference being had therein to the accompanying drawing.

The design relates to the form or configuration and ornamentation of a reflector for artificial lights.

The drawing shows a side elevation, partly broken away, of a reflector embodying my design.

The form of the body of the reflector is nearly that of a segment of a hollow sphere A and surmounted by a ring B. The outer surface of the spherical part of the body is practically covered by prisms C, arranged spirally

and side by side, as shown. The inner surface of the body is smooth, as indicated at the broken part.

The reflector is composed of transparent glass, and the external ornamentation therefore shows through.

The edge of the reflector is scalloped and beaded, as shown.

What I claim as my invention, and desire to secure by Letters Patent, is—

The design for a reflector for artificial lights, as shown and described.

In testimony whereof I affix my signature in presence of two witnesses.

OTIS A. MYGATT.
